[57] CLAIM

The ornamental design for a sensor line fitting for a respiratory system, as shown.

DESCRIPTION

FIG. 1 is a perspective view of a sensor line fitting for a respiratory system showing our new design;
FIG. 2 is a view in rear elevation thereof;
FIG. 3 is a view in side elevation thereof;
FIG. 4 is a view in front elevation thereof;
FIG. 5 is a bottom plan view thereof;
FIG. 6 is a top plan view thereof; and
FIG. 7 is a cross-sectional view taken on line 7—7 of FIG. 6.

FIG. 1
